UNITED STATES PATENT OFFICE.

FRANK WOJTKOWSKI AND DOMINIK RADZISZEWSKI, OF CHROME, NEW JERSEY.

PADLOCK

1,130,787.

Specification of Letters Patent.

Patented Mar. 9, 1915.

Application filed November 25, 1914. Serial No. 873,970.

To all whom it may concern:

Be it known that we, FRANK WOJTKOWSKI and DOMINIK RADZISZEWSKI, subjects of the Czar of Russia, residing at Chrome, in the county of Middlesex and State of New Jersey, have invented certain new and useful Improvements in Padlocks, of which the following is a specification.

This invention relates to new and useful improvements in padlocks.

The primary object of this invention is to provide a portable lock in the nature of a padlock and which requires two keys for the complete release of the locking member or hasp.

A further object is to provide a two key padlock operable only upon the successive manipulation of each of the keys, the lock casing having key holes capable of receiving either of the keys.

A still further object is to provide a padlock having two manipulating keys, one of the keys being adapted in the unlocking operation to retract a bolt while the other shifts the keeper but in the locking operation the first named bolt engaging key is solely employed for both projecting the bolt and reshifting the keeper to its locked position.

With these general objects in view and others that will appear as the nature of the invention is better understood, the same consists in the novel combination and arrangement of parts hereinafter fully described, illustrated in the accompanying drawings and pointed out in the appended claims.

In the drawings forming a part of this application and in which like designating characters refer to corresponding parts throughout the several views: Figure 1 is a side elevation of the device. Fig. 2 is an end elevation thereof. Fig. 3 is a transverse sectional view taken upon line III-III of Fig. 5. Fig. 4 is a central longitudinal sectional view taken through the device with the elements in their locked positions. Fig. 5 is a similar view with the locking elements released. Fig. 6 is a top plan view of the device partially broken away and with the top of the casing re-

moved. Fig. 7 is a perspective view of the device partially broken away and with the top of the casing removed. Fig. 8 is a perspective view of the locking bolt. Fig. 9 is a perspective view of the shiftable locking keeper; and Figs. 10 and 11 are perspective views of the two keys for operating the lock.

Referring more in detail to the drawings, the device broadly consists of a portable lock having a box-like casing 10 for inclosing lock mechanisms operable by means of keys 11 and 12 insertable within the openings 13 and 14 in the end 21 of the casing, a hasp 15 forming a part of the securing means, the said hasp being connected to the top plate 16 of the casing by means of a chain 17 having its opposite ends secured within an opening 18 of the hasp and a staple 19 upon the said top plate.

A shiftable bolt 25 is positioned longitudinally slidable within the casing being supported by a shelf 26 therein and guided by opposite ways 27 beneath the said shelf. A leaf-spring 28 has one end thereof secured as at 29 to the end of the shelf adjacent the lock end 21 while the free end of said spring is normally depressed within a longitudinal slot 30 of the shelf and is in engagement with the upper face of the bolt 25 and is adapted to seat within the notches 31 and 32 in the upper face of the bolt. One end of the bolt is in the form of a sharpened finger 33 which is adapted to pass through a perforation 34 of the hasp, which perforation is provided in the free end of the hasp that is inserted through the hasp opening 35 of the casing plate 16 when the lug 36 of the hasp engages the outer face of the said top plate.

When the bolt 25 is in its locked position, the spring 28 engages the notch 32 of the bolt and prevents a retracting or unlocking of the bolt and the key 11 which is provided with a single ward 37 may then be inserted through the key-hole opening 13 and the ward 37 inserted through the transverse perforation 38 of the bolt which enters the notch 32 and whereby the said ward will contact the free end of the spring 28 and disengage the same from the notch 32, there-

by allowing a retracting movement of the bolt by an outward impulse exerted upon the said key 11 and in which manner as will be apparent the bolt will be entirely disengaged from the securing hasp.

A partition 39 is provided in the casing at a point between the shelf 26 and the bottom wall 40 of the case, the said partition being positioned parallel to both the said shelf 10 and wall and is provided with a central longitudinal slot 41 therethrough. A keeper 42 mounted upon an operating plate 43 is slidably positioned within the casing with the said plate 43 slidably mounted in opposite ways 44 carried by the partition 39 and having the said keeper 42 extending through the end slot 45 of the partition 39. The keeper is provided with a socket perforation 46 through its upper portion and the said 15 perforation is at all times in alignment with the bolt end 33 while a transverse notch 47 of the keeper is at all times in alignment with the lower angular end 48 of the hasp when the hasp is positioned with its free 20 end within the casing and with its lug 36 engaging the top plate thereof.

Two pins 49 are slidably positioned within yokes 50 carried by the partition 39 and spanning the slot 41 thereof in such a manner that the said pins normally rest of their own weight upon the upper surface of the keeper operating plate 43 and extending through the said slot while the operating plate is provided with two spaced transverse 30 perforations 51 adapted to receive the said pins 49 when the keeper is in its locked position as illustrated in Fig. 1. The plate 43 is provided with a similar third perforation 52 farther removed from the keeper 42 than 35 the perforations 51 and the said perforation 52 is adapted to receive one of the pins 49 when the keeper is in its unlocked position and flatly engaging the inner face of the end wall 53 of the casing as illustrated in Fig. 2.

When the elements are in their unlocked position as illustrated in Fig. 2 and with the hasp inserted within the casing ready to be locked therein, the key 11 may be inserted through the key opening 14 and the ward 37 of the key pressed against the pin 49 which is within the plate perforations 52 and the said pin being thereby forced out of the said opening, the key 11 may be moved outwardly of the casing and drawing the operating plate as well as the keeper longitudinally of the casing and so as to engage the keeper notch 47 with the hasp end 48 in its locked position and at which time the two pins 49 will both drop into the plate perforations 51 upon removing the said key 11. The key 11 will then be inserted through the key-hole opening 13 and upon engaging the ward 37 with the perforation 38 of the bolt 25, the key may be pushed inwardly, thus sliding

the bolt 45 longitudinally and projecting 65 the locking end 33 thereof through the hasp perforation 34 and the keeper socket perforation 46, while upon removing the key 11 the free end of the spring 28 will drop into the notch 32 of the bolt and prevent a return 70 movement of the bolt when the key is removed from the lock. It will be noted that the notches 31 and 32 are inclined for affording abutments 54 at their forward ends and sloping rearwardly for allowing the 75 spring 28 to readily ride upon the bolt during its projecting movement.

When desired to unlock the elements, the two keys are employed by inserting the key 11 through the opening 13 and disengaging 80 the spring 28 from the notch 32 by means of its ward 37 as hereinbefore described and at which time the bolt may be retracted. The key 12 is then inserted through the key opening 14 and its two wards 55 brought 85 into engagement with the engaging ends of the pins 49 through the perforations 51 and such pins being thus removed from the said perforations, the plate 43 and its keeper 42 are slidably moved out of engagement with 90 the keeper to the unlocked position as shown in Fig. 5 and with one of the pins 49 engaging within the perforation 52 for retaining the keeper and plate in its unlocked position until again actuated by the key 11 as here- 95 inbefore set forth.

The manner of locking and unlocking the hasp from the casing mechanism having been described, it will be understood that the hasp and the chain 17 are together employed 100 for encircling the desired elements after the manner of the swinging hasp or yoke of the ordinary padlock or in other words, when the hasp is entirely removed from the casing, the chain may be passed around such 105 members as bars or through staples or rings and when the hasp is in locked engagement with the casing mechanism, such elements will be firmly secured together.

While the forms of the invention herein 110 shown and described are what are believed to be preferable embodiments thereof, it is nevertheless to be understood that minor changes may be made in the form, proportion and details of construction without departing from the spirit and scope of the invention as set forth in the appended claims.

What is claimed as new is:—

1. A lock comprising a casing having an opening in one wall thereof, a hasp positionable within said opening and provided with a perforation adjacent its inner end and having an angular flange at its inner end; a slidably mounted keeper within said casing having a perforation and a side notch there- 120 in in normal alignment with the perforation and extension respectively of the hasp when the hasp is in its closed position, and a lock- 125

ing bolt positioned through the perforations of said hasp and keeper when the elements are in their locked positions.

2. A lock comprising a casing having an opening in one wall thereof, a hasp positionable within said opening and provided with a perforation adjacent its inner end and having an angular flange at its inner end, a slidably mounted keeper within said casing having a perforation and a side notch therein in normal alinement with the perforation and extension respectively of the hasp when the hasp is in its closed position, a plate to which the said keeper is secured and provided with perforations therethrough, locking pins slidably transversely of the said plate and adapted for entering the said plate perforations when the keeper is in its locked position, and a slidable locking bolt positioned in alinement with the perforations of said hasp and keeper.

3. A lock comprising a casing, a shelf and a partition within the said casing parallel to each other and each provided with a central longitudinal slot and the said partition also having an end opening, an operating plate slidably mounted upon said partition and provided with perforations therethrough registering with the slot of said partition, a keeper secured to one end of said plate and projecting through the end opening of said partition and provided with a perforation therethrough and a notch in one face thereof, locking pins slidably mounted in said casing projecting through the slot of said partition and seated within the perforations of said plate when the keeper is in its locked position, a hasp having one end thereof positioned within said casing and provided with an angular extension in engagement with the notch of said keeper in its locked position.

4. A lock comprising a casing, a shelf and a partition within the said casing parallel to each other and each provided with a central longitudinal slot and the said partition also having an end opening, an operating plate slidably mounted upon said partition and provided with perforations therethrough registering with the slot of said partition, a keeper secured to one end of said plate and projecting through the end opening of said partition and provided with a perforation therethrough and a notch in one face thereof, locking pins slidably mounted in said casing projecting through the slot of said partition and seated within the perforations of said plate when the keeper is in its locked position, a hasp having one end thereof positioned within said casing and provided with an angular extension in engagement with the notch of said keeper when in its locked position, the said hasp being provided with a perforation

therethrough positionable in alinement with the perforation of said keeper, a slideable bolt upon said shelf and projecting through the perforations of said hasp and keeper when the elements are in their locked positions.

5. A lock comprising a casing, a slotted shelf positioned therein, a hasp provided with an angular extension and a perforation adjacent one end thereof and positionable within the said casing, a bolt member slidably mounted upon said shelf and having inclined notches in its upper face and being further provided with a perforation intersecting one of the said notches, a leaf spring having one end thereof secured to said shelf and having its other end in normal engagement with the said bolt member and in seating engagement with the notch which is provided with the perforation when the bolt member is in its locked position, a hasp member in the path of movement of the said bolt member, a shifting key for the said bolt member provided with a ward adapted for engaging the free end of said spring when projected through the said perforation and spring engaged notch of the lock member.

6. A lock comprising a casing, a slotted partition within said casing, a hasp having a terminal angular extension and a perforation and positionable within the said casing, a slide plate carried by the said partition and having three perforations therethrough in alinement with the slot of the partition, a keeper upon said plate provided with a notch in alinement with the hasp extension, locking pins slidably mounted through said slot transversely of the partition and in normal contact with said plate, each of the same being positioned within the perforations of the plate when the keeper is in its locked position and one of said pins being seated within another one of said perforations when the keeper is in its unlocked position.

7. A lock comprising a casing, a slotted shelf positioned therein, a hasp provided with an angular extension and a perforation adjacent one end thereof and positionable within the said casing, a bolt member slidably mounted upon said shelf and having inclined notches in its upper face and being further provided with a perforation intersecting one of the said notches, a leaf spring having one end thereof secured to said shelf and having its other end in normal engagement with the said bolt member and in seating engagement with the notch which is provided with the perforation when the bolt member is in its locked position, a hasp member in the path of movement of the said bolt member, a shifting key for the said bolt member provided with a ward adapted for engaging the free end of said spring when projected through the said perforation and spring engaged notch of the lock member.

ward adapted for engaging the free end of said spring when projected through the said perforation and spring engaged notch of the lock member, a slotted partition within said 5 casing, a slide plate carried by the said partition and having three perforations therethrough in alignment with the slot of the partition, a keeper upon said plate provided with a notch in alignment with the hasp extension, locking pins slidably mounted through said slot transversely of the partition and in normal contact with said plate, each of the same being positioned within 10 perforations of the plate when the keeper is 15 in its locked position and one of said pins being seated within another one of said perforations when the keeper is in its unlocked position.

In testimony whereof we affix our signatures in presence of two witnesses.

FRANK WOJTKOWSKI.

DOMINIK ^{his} X RADZISZEWSKI.
